UNITED STATES PATENT OFFICE

2,531,146

SYSTEM OF POLARIZING RELAYS

Andrew J. McConnell, Delmar, N. Y., assignor to
General Electric Company, a corporation of
New York

Application December 2, 1948, Serial No. 63,034

9 Claims. (Cl. 175—294)

1

This invention relates to a system of relaying and more particularly to the determination of the direction of a ground fault by means of directional ground relays.

One conventional method for determining the direction of a ground fault by means of directional ground relays requires polarization from a current transformer in a power transformer grounded neutral.

Another conventional method of obtaining the same result is to obtain potential polarization from a source of zero-phase-sequence potential such as three phase-to-ground potential transformers with secondaries connected in open delta.

Use of the first method depends upon having a power transformer with grounded neutral at the station where the directional ground relay is to be used. We shall assume for purposes of explaining my invention that such a transformer is not available (as is often the case).

Under such a condition the second conventional method of potential polarization may be employed. However, this method requires the installation of three phase-to-ground potential sources, such as potential transformers for polarization of the directional ground relays. This may be a costly installation at the higher voltages, especially if two potential transformers are not already available for energization of phase relays, meters, etc.

It is an object of this invention to provide a less costly means for polarization at a station where no polarizing current or potential is available.

In general my invention comprises a system for obtaining current or potential from a remote station having a polarization source, transmitting a quantity derived from that potential or current by means of carrier current to the station in which the directional ground relay is located, and using that derived quantity at the latter station to polarize the relay.

For an understanding of the invention and of the improvements herein disclosed, reference should be had to the following specification and the accompanying drawing in which Fig. 1 is a diagrammatic view of a power circuit showing the application of this invention thereto, and Fig. 2 is a diagrammatic view of a modification of a portion of the power circuit shown in Fig. 1.

Referring to the drawing in detail, there is shown in Fig. 1 a power system having stations A and B with transmission lines indicated as extending to an additional station C. At station A a power transformer 1 having a grounded

2

neutral 2 is available. Power is delivered by power transformer 1 to an electrical bus 3 of station A and thence through circuit breaker 4 of station A along transmission line 5 to circuit breaker 6 of station B from which it is fed to an electrical bus 7 of station B and thence through circuit breaker 8 to transmission line 9 leading to station C. It is assumed that another source of ground current is present at station C or at a point beyond.

On this power system as outlined above it is desired to provide directional ground relay protection at station B for a fault in the direction of station C, for example, at point X.

In considering the power system as thus far described, it will be noted that no means is available at station B to supply polarizing current or potential for a directional ground relay to be located at station B.

Since no power transformer is available at station B, the remaining conventional means of polarization would be the installation of three phase-to-ground potential transformers with secondaries connected in open delta, which, as previously mentioned, is costly under certain circumstances.

In order to obtain the desired protection I provide a system in which polarizing current is taken from the power transformer 1 of station A by means of current transformer 10 electrically connected to a modulator 11, which modulates a carrier current transmitter 12. Alternatively, the transformer may modulate an audio frequency wave which in turn modulates the carrier wave of transmitter 12. The modulated carrier wave is coupled by means of a coupling capacitor 13 to transmission line 5 and received by a carrier current receiver 15 through a coupling capacitor 14 at station B. The demodulated current or voltage at the output of receiver 15 may be amplified in an amplifier 16 where necessary and the output current of amplifier 16 is supplied to the polarizing coils 17 of a directional ground relay 18 located at station B. The coil 19 of directional ground relay 18 is supplied by three current transformers 20 located one in each phase between the bus 7 and circuit breaker 8 of station B. Line traps or filter circuits 21 are located at each end of the transmission lines 5.

By means of this system, direction relay 18 is supplied with a polarizing means from station A. Directional ground relay 18 will then trip breaker 8 for a fault in the direction of station C. This assumes, of course, that other breakers beyond station B have not been tripped by reason

of their lower time setting and that no blocking carrier system signal has been received from station C. Relay 18 will not trip circuit breaker 8 for a fault in the direction of station A.

For the purposes of illustrating my invention, I have shown in Fig. 1 a system whereby a polarizing current quantity derivative is transmitted from a remote station to a station having no source of polarizing current or potential in order to polarize a directional ground relay. However, it will be apparent that if a zero-phase-sequence potential is available at station A, a quantity derived from that voltage may be transmitted to station B in a similar manner by means of a carrier current channel to polarize a directional ground relay located at the latter station.

For example, referring to Fig. 2, a potential transformer 22 having a Y-connected grounded primary winding 23 connected to the bus 3 and an open delta connected secondary winding 24 connected to the modulator 11 can be used to energize the modulator 11 from the transformer 18 shown in Fig. 1.

By means of this system it is possible under certain circumstances to reduce to a fraction of present conventional installation costs the cost of obtaining current or potential polarization at a point remote from the polarization source.

In place of a carrier current system, other similar means for producing the same result, such as use of microwave radio transmission, may also be used.

Although an exemplary form of the invention has been shown in the accompanying drawing and described herein in detail, it is to be understood that the disclosures are not intended to be restrictive but that each may embody various modifications in detail structure without departing from the spirit of the invention or the scope of the appended claims.

What I claim as new and desire to secure by Letters Patent of the United States is:

1. In an electrical power system an arrangement for polarizing a relay associated with the system in accordance with an electrical quantity derived from a Y-connected power transformer having a grounded neutral and located at a point remote from the relay, said arrangement comprising a carrier current system, means for actuating said carrier system including a current transformer energized by the flow of current between the neutral of the power transformer and ground during a fault condition, and means operable in response to the actuation of said carrier system for supplying a polarizing quantity to said relay.

2. In an electrical power system an arrangement for polarizing a relay associated with the system in accordance with an electrical quantity derived from a Y-connected power transformer having a grounded neutral and located at a point remote from the relay, said arrangement comprising a carrier current system, means for actuating said carrier current system from a polarizing source remote from said relay, and means operable in response to the actuation of said carrier system for supplying a polarizing quantity to said relay.

3. In an electrical power system an arrangement for polarizing a relay associated with the system in accordance with an electrical quantity derived from a source of zero-phase-sequence potential located at a point remote from the relay, said arrangement comprising a carrier current

system, means for actuating said carrier current system including means operable in response to the voltage produced from said source of zero-phase-sequence potential during a fault condition, and means operable in response to actuation of said carrier system for supplying a polarizing quantity to said relay.

4. In an electrical power system an arrangement for polarizing a relay associated with the system in accordance with an electrical quantity derived from three phase-to-neutral sources of potential the secondaries of which are connected open delta and located at a point remote from the relay, said arrangement comprising a carrier current system, means for actuating said carrier current system including means operable in response to the voltage produced across the open delta during a fault condition, and means operable in response to actuation of said carrier system for supplying a polarizing quantity to said relay.

5. In an electrical power system an arrangement for polarizing a relay associated with the system in accordance with an electrical quantity derived from three phase-to-neutral potential transformers having their secondary windings connected in open delta and located at a point remote from the relay, said arrangement comprising a carrier current system, means for actuating said carrier system including means operable in response to the voltage produced across the open delta during a fault condition, and means operable in response to actuation of said carrier system for supplying a polarizing quantity to said relay.

6. In an electrical power system an arrangement for polarizing a relay associated with the system in accordance with an electrical quantity derived from a Y-connected power transformer having a grounded neutral and located at a point remote from the relay, said arrangement comprising a carrier current system, means for actuating said carrier current system in response to the flow of current between the neutral of the power transformer and ground, and means operable in response to the actuation of said carrier system for supplying a polarizing quantity to said relay.

7. In an electrical power system an arrangement for polarizing a relay associated with the system in accordance with an electrical quantity derived from the system at a point remote from the relay, said arrangement comprising a carrier current system, means for actuating said carrier current system in response to an unbalanced voltage condition on the system occurring during a fault condition on said system, and means operable in response to actuation of said carrier system for supplying a polarizing quantity to said relay.

8. In an electrical power system an arrangement for polarizing a relay associated with the system in accordance with an electrical quantity derived from the system at a point remote from the relay, said arrangement comprising means for transmission of an electrical signal, means for actuating said signal means from a polarizing source remote from said relay, and means operable in response to the actuation of said signal means for supplying a polarizing quantity to said relay.

9. In an electrical power system an arrangement for polarizing a relay associated with the system in accordance with an electrical quantity derived from the system at a point remote from

the relay, said arrangement comprising a carrier current system in which a modulator modulates an audio tone which in turn modulates a carrier current transmitter, means for actuating said carrier current system from a polarizing source remote from said relay, and means operable in response to the actuation of said carrier system for supplying a polarizing quantity to said relay.

ANDREW J. McCONNELL.
